CATALYTIC DESULPHURIZATION PROCESS

Miller Wade Conn, Bartlesville, Okla., assignor
to Phillips Petroleum Company, a corporation
of Delaware

Application February 12, 1942, Serial No. 430,686

4 Claims. (Cl. 196—27)

This invention relates to a process of treating hydrocarbons and relates more particularly to desulphurization of hydrocarbon oils, particularly petroleum, shale oil and other mineral oils, and their products.

There are various types of sulphur compounds present in mixtures of hydrocarbons comprising petroleum, coal tar, shale oils and the like. These types of sulphur compounds may be generally classified as (1) The aliphatic and aromatic mercaptans, sulphides and disulphides, which for the sake of brevity are termed non-heterocyclic sulphur compounds, and (2) Heterocyclic sulphur compounds, such as thiophenes and thiophanes.

The presence of the aforementioned sulphur compounds and the like in hydrocarbon oils are known to be detrimental to automotive fuels, aviation fuels, solvent naphthas, and the like, and oftentimes it is highly essential to remove as nearly as completely all sulphur-bearing bodies from such oils. In recent years many processes have been advanced for the removal of organic sulphur compounds from hydrocarbon oils and bauxite (as described by James E. Pew and A. E. Buell under the title of "Catalytic desulphurization solves problem in high-sulphur distillates" in National Petroleum News for October 2, 1940) has been found to be a very effective catalytic desulphurization catalyst. It is believed that the mechanism of the catalytic reaction may proceed according to Equation 1 below which is typified by butyl mercaptan in the presence of bauxite catalyst under proper conditions of temperature and pressure:

I have discovered that, probably inasmuch as Equation 1 is promoted by the catalytic action of the bauxite under elevated temperatures and moderate pressures, a reversal of this chemical equation takes place considerably at normal conditions of temperature and pressure to an extent that will result in only a partially desulphurized oil. The reversal of Equation 1 may be exempli-

fied by Equation 2 to show the recombination of hydrogen sulphide and olefinic hydrocarbons to form mercaptans at normal conditions of temperature and pressure:

According to chemical theory, Equation 1 and Equation 2 as set forth above will proceed until chemical equilibrium is established according to Equation 3 hereinafter set forth:

As is well known to those skilled in the art, the forward reaction of Equation 3 is promoted by the catalyst and elevated temperatures and reduced pressures, while on the other hand the reverse reaction of Equation 3 is promoted by the absence of the catalyst and reduced temperatures and elevated pressures.

An object of this invention is to provide a method of treating hydrocarbon oils containing undesirable sulphur compounds comprising a new and novel means for catalytic desulphurization designed to greatly reduce the sulphur content of the desulphurized hydrocarbon oils.

A principal object of this invention is to provide an improved method of catalytic desulphurization of hydrocarbon oils, and particularly the removal of hydrogen sulphide and other sulphurous bodies to an extent to obtain greater degrees of catalytic desulphurization than hitherto known and/or practiced.

40 A further object of this invention is to provide a new and novel means for curtailing and reducing the extent of the reverse reaction shown in Equation 3 in order to secure and obtain a more completely desulphurized oil and one which will meet the so-called Doctor test and the most rigid corrosion test specifications.

Numerous other objects and advantages will appear from the following description taken in conjunction with the accompanying drawing which portrays diagrammatically one form of

apparatus which may be used in carrying out the present invention.

In accordance with my invention a hydrocarbon oil containing organic sulphur compounds, and especially mercaptans, as impurities, is vaporized and brought to from about 650° to about 800° F. and passed, in the presence or absence of added hydrogen at this temperature and at a pressure of from about atmospheric to about 100 pounds per square inch gauge into intimate contact with a solid desulphurization catalyst to effect catalytic desulphurization.

Examples of such catalysts are: fuller's earth, bauxite, other catalysts of the clay type, as described in U. S. 1,895,081 and 2,016,271; chromium ore (U. S. 2,016,272); vanadium ore (U. S. 2,075,171); tungsten ore (U. S. 2,075,172); molybdenum ore (U. S. 2,075,173); cadmium ore (U. S. 2,075,174); porous alumina (U. S. 2,112,931); zinc ore (U. S. 2,098,943); the catalysts described in U. S. 2,162,319; zirconium oxide (U. S. 2,206,921); and any other known or suitable solid desulphurization catalyst capable of converting, under the above conditions, the organic sulphur compounds and especially the mercaptans to hydrogen sulphide, and preferably adapted to be arranged in pervious beds of granular catalyst.

The effluent from the desulphurization step at essentially the temperature prevailing in the desulphurization unit is continuously withdrawn and while still at this temperature treated to remove the free hydrogen sulphide therefrom in order to prevent re-combination thereof with the hydrocarbon content and especially with the olefins.

This removal of hydrogen sulphide should be effected before, or at the latest simultaneously with, any appreciable cooling of the effluent. This may be accomplished in accordance with my invention in a number of ways among which are those set forth specifically below. The removal is effected under conditions such that the temperature of the entering effluent vapors is maintained for at least the beginning of the contact with the removal agent and preferably during a substantial portion of said contact. The conditions should be such that throughout the removal unit the concentration of free hydrogen sulphide is so low and the temperature of the mixture is such as to preclude any substantial reaction of said free hydrogen sulphide, having due regard for the law of mass action.

In one mode of sulphur removal, the hot vapors are passed through a bed of solid reagent capable of removing the hydrogen sulphide. Numerous solid reagents capable of reacting with and removing H₂S are well known to the art and need not be enumerated here. The temperature throughout the removal zone is preferably maintained at essentially that prevailing in the catalytic desulphurization tower.

Another mode of accomplishing the H₂S removal is to scrub the hot gases with a liquid medium adapted to dissolve, either by solution or reaction, the hydrogen sulphide in the effluent. Examples of such liquids are water, aqueous solutions of lower aliphatic alcohols such as methanol, ethanol, etc., aqueous solutions of alkalies such as alkali metal hydroxides, ammonium hydroxide, etc. In this way, by supplying the scrubbing medium in sufficient volume and at a sufficiently low temperature, the vapors are condensed at the same time as the hydrogen sulphide is removed, and at no time are conditions of H₂S concentration and temperature of effluent such that re-reaction of the hydrogen sulphide can occur.

Referring to the drawing, the sulphur-bearing oil is charged to the system by line 1A and feed pump 1 through line 2 to heat exchanger 3, thence via line 4 to the tube bank 5, said tube bank being disposed in heater 6, wherein the hydrocarbon oil is vaporized and super heated to temperatures in excess of 650° F.-700° F. say to about 750° F. From the tubular heater the super-heated hydrocarbon vapors pass through line 7 to catalyst towers 8 which may or may not be operated in parallel. In catalyst towers 8, under the conditions of temperature as specified above and pressures in the range of from about 25 to about 50 pounds gauge, the reaction expressed by Equation 1 set forth above proceeds to substantial completion with many sulphur-bearing hydrocarbon oils and particularly light straight run and natural gasolines. As the desulphurized hydrocarbon oils containing equivalent molecular quantities of olefinic hydrocarbons and hydrogen sulphide emerge from catalyst towers 8 through treating zone 15 in line 9 and thence in heat exchange relationship with the incoming charge in heat exchanger 3 there is appreciable recombination of hydrogen sulphide and olefinic hydrocarbons taking place as exemplified by Equation 2 set forth above.

The principal object of this invention is to provide for the addition of an "agent" to the hot sulphurous gases, such "agent" to exert a greater affinity for hydrogen sulphide than the olefinic hydrocarbons in order to reduce to a negligible quantity the chemical recombination of olefinic hydrocarbons and hydrogen sulphide as exemplified by Equation 2 set forth above.

The numerous agents employed within the scope of this invention may be roughly divided into two classes, namely, those exerting purely chemical affinity for hydrogen sulphide and those exerting physical and preferably solvent effects on hydrogen sulphide and at the same time being immiscible with the hydrocarbon oils. Among those agents exerting chemical affinity for hydrogen sulphide may be any of the well known metallic substances and their compounds such as iron, alkali metals and alkaline earth metals and others well known to the art. Among those substances known to exert a solvent effect on hydrogen sulphide and at the same time being substantially immiscible with the hydrocarbon oils are water and aqueous mixtures of some of the lighter alcohols and the like. These aqueous mixtures are not necessarily limited to solutes exerting purely a physical influence on H₂S, but may be capable of chemically reacting therewith such as alkalies, ammonia, etc.

In the practice of this invention any one or more of the above enumerated agents and the like may be disposed in zone 15 into which the superheated sulphur-bearing hydrocarbon vapors pass from the catalyst towers 8 while still subjected to substantially the conditions of temperature and pressure to which they were subjected in towers 8. In intimate contact with the said agents the effluent may be allowed to reach normal condition of temperature and pressure and thereby produce a desulphurized hydrocarbon oil substantially free of any recombined hydrogen sulphide and olefinic hydrocarbons which may be to such an extent to produce a product giving a positive Doctor test and exhibiting severe corrosion properties. From the influence and direct and intimate relationship with the said agent disposed within unit 15 the hot or cold hydrocarbon vapors may proceed via line 16

through heat exchanger 3, through line 10 to condenser 11 and thence through line 12 to an accumulator tank 13 for further processing if desired such as sweetening, etc., (in equipment not shown).

Treating unit 15 is designed for the rapid removal of the hydrogen sulphide formed in towers 8 by the desulphurization reaction, before the effluent has had a chance to cool to any material extent. By removing the hydrogen sulphide from the effluent before it has cooled to temperatures at which re-reaction can take place to any substantial degree, the occurrence of such re-reaction is effectively prevented.

Preferably unit 15 is located in such close proximity to the exit point of towers 8 that no appreciable cooling of the effluent can take place between towers 8 and the inlet to unit 15. Desirably the line 9 may be lagged to prevent heat loss. Also the unit 15 may advantageously be lagged to maintain the temperature therein by preventing loss of heat therefrom.

Unit 15 may take any form which will accomplish essentially complete removal of free H₂S from the catalytic desulphurization effluent before or, at the latest simultaneously with the cooling of the effluent to a point at which appreciable re-reaction might occur.

In one form, unit 15 may be a chamber or tower, preferably lagged, filled with a pervious or porous mass of granular solid material which is adapted to react with the hydrogen sulphide and fix the same. In such case the unit 15 may be maintained throughout at essentially the same temperature as that prevailing in towers 8, and the effluent from unit 15 will be at substantially the same temperature as that in towers 8. Or the temperature may gradually lower as the vapors pass through the unit, the reduction in concentration of free hydrogen sulphide by the reaction with the solid reagent being such that as to effectively counteract any tendency for Reaction 2 to occur due to the progressively lower temperature encountered. It will be understood that the tendency for Equation 2 to proceed depends on the concentration of hydrogen sulphide as well as the temperature of the reaction mixture.

The pressure in unit 15 may be substantially that in towers 8, namely from about atmospheric to about 100 pounds per square inch gauge. Usually substantially atmospheric pressure is preferred.

In another embodiment, unit 15 may take the form of a scrubbing tower in which the hot effluent from the desulphurization catalyst intimately contacts, as in countercurrent relationship, a liquid medium capable of reacting with and/or dissolving the hydrogen sulphide content thereof. In such case the hot effluent is condensed at the same time as it is freed of hydrogen sulphide, and thereby converted to liquid form, its temperature being rapidly brought to well below the point at which any recombination with any free hydrogen sulphide might occur. A volume of relatively cold liquid medium sufficient to effect complete condensation of all of the hydrocarbons in the effluent should be used. Where the liquid medium boils at temperatures well below that of the effluent vapors, it is necessary to introduce a sufficiently large volume of liquid medium at a sufficiently low temperature that the entire effluent is condensed while the liquid medium remains in the liquid phase. In some cases maintenance of the desulphurization tower and the H₂S removal unit at an elevated

pressure may be resorted to in order to raise the boiling point of the liquid medium and lower the volume thereof necessary to be supplied.

When practicing the invention in accordance with the embodiment just described, the hydrocarbon condensate from scrubbing unit 15 may be passed via line 17 directly to accumulating tank 13. If desired a unit 18 may be interposed in line 17 for the removal of any last traces of the scrubbing medium employed in unit 15.

Two examples describing the practice of this invention will be set forth:

Example 1

At some point in line 9, preferably as close to the exit from towers 8 as possible, a tower 15 of suitable size may be placed through which the sulphur-bearing hydrocarbon vapors may pass at greatly reduced linear velocities, there being disposed in said tower any of the well known chemical agents exerting a greater affinity for hydrogen sulphide than the olefinic hydrocarbons resulting from the catalytic action in towers 8. Alternate towers 15 may be provided for use while towers 15 containing spent reagents may be regenerated in order to obtain continuous operation. The chemical agents used in the towers 15 may be any of the well known chemical reagents known to be corroded by hydrogen sulphide or to react therewith and to have a much greater affinity for hydrogen sulphide than the olefinic hydrocarbons produced as a result of the catalytic action taking place in catalyst chambers 8.

Example 2

The H₂S removal unit 15 takes the form of a scrubber located at a convenient point in line 9, in which may be placed as scrubbing agents any of the well known solvents immiscible with hydrocarbon oils and/or vapors and having appreciable solvent power for hydrogen sulphide such as water and/or methanol. The sulphur-bearing hydrocarbon oils leaving the towers 8 in vaporized form will enter the lower end of the scrubber, which may be of any of the well known types and pass in counter current flow in intimate contact with the hydrogen sulphide solvent such as water or methanol. The action of the solvent will be twofold, that is, to dissolve the hydrogen sulphide from the hydrocarbon vapors and/or liquid hydrocarbons and to simultaneously cool and condense the hydrocarbon vapors to condition of temperature at which no recombination of the olefinic hydrocarbons and hydrogen sulphide will occur as exemplified by Equation 2 set forth above.

Many other applications of the present disclosure will be obvious to those skilled in the art of catalytic desulphurization and general chemical refining.

I claim:

1. The process of desulphurizing hydrocarbon oil containing organic sulphur compounds as impurities which comprises vaporizing the oil and heating to a temperature within the range of from about 650 to about 800° F., contacting the vapors at substantially said temperature with a solid desulphurization catalyst adapted to convert said sulphur compounds to hydrogen sulphide, removing the effluent vapor from said contacting step, directly scrubbing said effluent while at substantially said temperature at the beginning of the scrubbing step by suddenly, rapidly and thoroughly contacting the effluent vapor with a sufficient quantity of relatively cold liquid medium adapted to dissolve substantially all of the hydrogen sul-

phide therefrom and simultaneously cool the effluent vapor before said hydrogen sulphide has had an opportunity to re-react with the hydrocarbon in the effluent due to cooling before thoroughly contacting, said scrubbing step taking place under conditions that the hydrocarbon content of said effluent is substantially condensed to liquid phase, and recovering the resulting liquid substantially free from hydrogen sulphide.

2. The process of claim 1 in which said liquid medium is water.
3. The process of claim 1 in which said liquid medium is an aqueous solution of a lower aliphatic alcohol.
4. The process of claim 1 in which said liquid medium is an aqueous solution of methyl alcohol.

MILLER WADE CONN.
